FINGER RING, BRACELET, AND THE LIKE

Josef Pejchar, Corona, N. Y.

Application May 18, 1934, Serial No. 726,270

8 Claims. (Cl. 63—27)

My present invention relates to articles of personal wear or adornment, such as finger rings, bracelets, wrist-watch straps, ear rings, pendants, and the like. The object of my invention is to provide a simple, efficient and ornamental connection between a body member and a setting member holding a gem or other ornamental object.

According to my invention, the setting member has a plurality of prongs for holding the gem or other ornamental object, and at least two of such prongs, located at opposite portions of the setting member, serve not only as holding elements for such object, but also for connecting the setting member with other elements, for instance with the two ends of a body member, either directly or indirectly. Thus according to my invention at least two oppositely located prongs of said setting member have a double function.

A number of embodiments exemplifying my invention are illustrated by the accompanying drawing, in which Fig. 1 is a side elevation of a finger ring made according to my invention; Fig. 2 shows the same ring partly in elevation and partly in section; Fig. 3 is a top view of such ring; Fig. 4 is a perspective view of the pronged setting member; Fig. 5 is a top view of another embodiment in which the body member of the finger ring has a form different from the one shown in Figs. 1, 2, and 3; Figs. 6 and 7 illustrate another finger ring according to my invention, in side elevation (partly in section) and top view respectively; Fig. 8 illustrates still another finger ring embodying my invention, in side elevation with parts in section; Fig. 9 is a top view of the ring shown in Fig. 8, and Fig. 10 shows the blank from which the setting member employed in Figs. 8 and 9 is formed; Fig. 11 is a view similar to Fig. 8, and showing a slightly different form of the body member; Fig. 12 is a perspective view of another form of body member which I may use, for instance as a substitute for those shown in the preceding figures, and Fig. 13 shows a pendant or like article embodying my invention.

In Figs. 1, 2, and 3 I have shown a metallic body member 20 of annular form adapted to form the main portion of a finger ring. This member has spaced enlarged ends 21 with centrally located openings 22 of rectangular or other suitable shape. These openings, which extend from the inner surface of the ring to its outer surface, are adapted to receive two opposite prongs 23 of a metallic setting member 24. The latter is preferably curved in one direction to correspond to the curvature of the body member 20, as shown

in Figs. 1, 2 and 4. The setting member has additional prongs 25 located laterally, the four prongs 23, 25 serving to hold an ornamental object 26, which may be a precious or semi-precious stone, or an imitation jewel, or any other suitable object. When such object is a stone or jewel, the prongs are properly shaped to form seats for holding the stone or jewel, in any well-known or approved manner. In this case the setting member is preferably apertured, as indicated at 27, so that the jewel will show to better advantage.

The prongs 23, 25 are formed from extensions or tabs which originally extend outwardly from the outer edge of the setting member 24 and are subsequently bent to extend substantially at right angles to the plane of such member, as indicated in Figs. 2 and 4. The two prongs 23 are preferably tapered as illustrated. When in the position shown in Fig. 4, the prongs 23 are readily inserted into the openings 22 of the body member 20, 21, as indicated in Fig. 2. The jewel 26 being then placed in position, the free ends of the prongs 23, 25 are bent inwardly to hold the jewel as shown in Fig. 1, thus completing the manufacture of the finger ring.

It will be noted that each of the prongs 23 has a double function, namely, first, to hold the jewel or other ornamental object 26, and second, to connect the setting member 24 with the body member 20. Preferably, the prongs 23 extend loosely through the openings 22, the width of the latter, measured circumferentially of the ring, being considerably greater than the thickness of the said prongs. Thus a certain amount of play, circumferentially of the ring, is afforded for the ends 21 of the body member 20 relatively to the setting member 24. As the split body member 20 is naturally somewhat elastic, this play enables the ring to adjust itself, within certain limits, to fingers of different sizes, and moreover enables the ring to be readily removed when desired, and prevents it from cutting into the flesh, thus avoiding discomfort and the danger of infection.

While I prefer to have a loose connection between the setting member 24 and the body member 20, this is not absolutely essential, and I might connect these two members rigidly, for instance by soldering the prongs 23 in the openings 22, and still retain some of the advantages of my invention.

The construction shown in Fig. 5 differs from the one described above only by the shape of the metallic body member or rather of its ends 21', which are shown of a shape simulating the looped ends of a cord. Through the openings 22' of

these ends extend the prongs 23 of the setting member 24, which is shown of exactly the same construction as in Figs. 1 to 4. The prongs 23 preferably pass through these openings loosely, 5 so as to give the ends 21' some play in a circumferential direction, in the same manner as explained with reference to Figs. 1 to 4, but if desired, the ends 21' may be soldered or otherwise rigidly secured to the setting member 24.

10 In the two constructions so far described, the ends of the body member are connected directly with two prongs (23) of the setting member. In Figs. 6 to 11 I have shown three forms of my invention in which this connection is made indirectly, through an intermediate connecting member.

15 In Figs. 6 and 7, the setting member 24 with its prongs 23, 25 may be of the same character as set forth above in connection with Figs. 1 to 5. The prongs 23, instead of fitting directly into openings in the ends of the body member, are passed outwardly through openings 28 in connecting members 29, here shown as rectangular links curved circumferentially to conform to the shape of the ring. One of the transverse members of each link is hooked into the adjacent prong 23, the other transverse member extends through an eye or opening 22" in the respective end 21" of the body member 20". The connections at one or 20 both ends of each link 29 may be rigid, as by soldering. I prefer, however, that each end of each link should form a hinge or pivotal connection with the adjacent body or setting member, to permit a slight motion about an axis parallel 25 to the axis of the finger ring. Furthermore, I prefer that the width of the opening 28, measured circumferentially of the ring, should be so much greater than the thickness of the prongs 23 as to permit a certain amount of circumferential play 30 of the connecting member 29 relatively to the setting member 24. If desired, similar circumferential play might be permitted at the points where the connecting members 29 fit into the ends 21" of the body member 20". It will be noted that 35 the two eyes 22" are in the same plane, which is perpendicular to the axis of the ring.

40 In the construction illustrated by Figs. 8, 9, and 10, the body member 20" and the connecting members 29 are of the same construction as in Figs. 6 and 7. The setting member is of a construction somewhat different from the one shown 45 in Figs. 1 to 7. Fig. 10 shows the blank from which I form the setting member of Figs. 8 and 9. This member has an apertured rectangular portion 24a with projections or tabs 25a extending outwardly and adapted to be bent upwardly and inwardly to form two opposite prongs, corresponding in function to the prongs 25 of Figs. 1 to 7. The other two prongs are formed from a central 50 strip extending lengthwise of the rectangular portion 24a and slit or cut at its middle, as indicated at 30. This forms two strips or tabs 23a which extend from the inner edge of the apertured portion 24a and after being bent up constitute 55 fastening prongs 23a to hold the jewel or other ornamental object 26. One of the transverse members of each connecting member or link 29 is hooked into the adjacent prong 23a, in the 60 same manner as described in connection with Figs. 6 and 7. The other transverse member of the connecting member 29 is passed through the openings 22" at the ends 21" of the body member 20", in the same manner as in Figs. 6 and 7.

65 The construction shown in Fig. 11 differs from 70 the one illustrated by Figs. 8, 9, and 10 only in

this respect that the ends 21a of the body member 20" are bent outwardly (instead of inwardly) to form the openings or eyes 22a.

75 In Fig. 12 I have shown a body member 20b formed by a double flexible cord which may be bent into the shape of a split ring as illustrated, with loops or eyes 22b corresponding to the openings 22' of Fig. 5. The two runs of the cord are held together by metal clamps 31. The body member 20b might be formed of a single piece 10 of cord the ends of which would be fastened in one of the clamps 31, preferably the middle clamp. Instead of this, the member 20b might be made in two pieces, with their four ends fastened in the central clamp 31. The body member shown 15 in Fig. 12 may be used as a substitute for the body member of Fig. 5, or of Fig. 11, or of any of the other embodiments of my invention described above.

20 The forms of my invention described so far have an annular body member with spaced ends connected directly or indirectly with the setting member. These constructions are adapted for use in annular articles such as finger rings, bracelets, wrist-watch straps, and the like. My invention, however, is not limited to cases where the body member is annular. It may, for instance, be used with ear rings, pendants and other articles.

25 As an example of such other uses, I have shown 30 in Fig. 13 a portion of a body member 20c, which may be, for instance, a link of a necklace or chain, or part of a cord of the character shown in Fig. 12, or a loop forming part of an ear ring, etc. At 31' I have indicated a metal clamp for 35 fastening the two runs or strands of this body member, so that the end 21c will form an eye or opening 22c to receive one of the prongs 23 of the setting member 24, which is shown as of substantially the same character as in Figs. 1 40 to 5. As in the forms of my invention described above, this prong 23 has the double function of holding the jewel or other ornament 26 and of connecting the body member 20c with the setting member 24.—In some cases, one or more 45 additional setting members may be connected with the first. Thus Fig. 13 shows a second setting member 24c connected with the first by means of a link or connecting member 29' of the same character as the members 29 of Figs. 50 6 to 10.

55 For the sake of clearer illustration, the jewel or other ornamental object has been omitted at various places in the drawing, but it will be understood that wherever I have shown a setting member with prongs, such prongs are intended to hold an ornamental object.

60 I have stated, with respect to some forms of my invention, that the connection of the setting member with the body member (whether direct or indirect) may be rigid instead of loose; this remark will apply to all the embodiments illustrated. Generally, however, the loose connection will be preferred.

65 Various modifications may be made without departing from the nature of my invention as defined in the appended claims.

I claim:

70 1. An article of the character described, comprising a setting member having a plurality of holding prongs extending on the same side of said member, an ornamental object set between said prongs and held by them, and a body member having spaced ends connected with two opposite holding prongs of said setting member.

2. An article of the character described, comprising a setting member having a plurality of prongs, an ornamental object held by said prongs, and a body member having spaced ends connected with two opposite holding prongs of said setting member. 5
3. An article of the character described, comprising an annular body member the ends of which are spaced from each other, a setting member located between said spaced ends and provided with a plurality of prongs two of which align circumferentially of the body member and are connected with said ends of the body member, and an ornamental object held by said prongs. 10
4. An article of the character described, comprising an annular body member the ends of which are spaced from each other, a setting member located between said spaced ends and provided with a plurality of prongs two of which align circumferentially of the body member and are connected loosely with said ends of the body member to permit circumferential play, and an ornamental object held by said prongs. 15
5. An article of the character described, comprising an annular body member the ends of which are spaced from each other, a setting member located between said spaced ends and provided with a plurality of prongs, an ornamental object held by said prongs, and connecting members extending circumferentially of the body member and interposed between the respective ends of the body member and prongs located at opposite ends of the setting member. 20
6. An article of the character described, comprising an annular body member the ends of which are spaced from each other, a setting member located between said spaced ends and provided with a plurality of prongs some of which extend from the outer edge of the setting member and others from the inner edge thereof, two of said prongs being connected with said ends of the body member, and an ornamental object held by said prongs. 25
7. An article of the character described, comprising a setting member having a plurality of holding prongs, an ornamental object held by said prongs, and elements connected with two opposite holding prongs of said setting member. 20
8. An article of the character described, comprising a setting member having longitudinally aligning holding prongs at opposite ends and lateral holding prongs, an ornamental object held by said prongs, and elements connected with said longitudinally aligning opposite prongs of the setting member. 25

JOSEF PEJCHAR.
